REFRIGERATING APPARATUS

Andrew A. Kucher, Dayton, Ohio

Application November 23, 1936, Serial No. 112,309

5 Claims. (Cl. 62—89)

The present invention relates to refrigeration and particularly to the method and manner of directing air within the storage compartment.

In household refrigerators now in use, the heat absorber, in the form of an evaporator, is usually placed in the upper part of the insulated compartment and the air circulates due to convection, absorbing heat from the food and giving up heat to the evaporator.

10 One of the objects of the present invention is to impose barriers to free circulation of air within the food storage compartment.

It is another object to cause air to flow in zigzag fashion in the storage compartment.

15 Another object of the invention is to increase the reflecting surface within the storage compartment.

A further object is to utilize imperforate shelves as the barriers and to arrange the shelves so 20 that the air flows in a zigzag path, the shelves being imperforate providing relative large reflecting surfaces.

Further objects are to provide a slideable shelf 25 having a portion adapted to extend around an edge of the shelf and also above the shelf and having another portion adapted to extend around the lug on the lining which supports the shelf; to provide a three point suspension for the shelf and in which one of the supports prevents tilting 30 of the shelf and the other two prevent respectively, forward and sidewise movement of the shelf.

Further objects and advantages will be apparent from the following description, reference being had to the accompanying drawing wherein 35 a preferred form of embodiment of the present invention is clearly shown.

Referring to the drawing:

Fig. 1 is a perspective view of my improved refrigerator showing the food compartment door 40 open;

Fig. 2 is a front view of the refrigerator also showing the door open;

Fig. 3 is a longitudinal sectional view taken on line 3—3 of Fig. 2;

45 Fig. 4 is a view showing in section a portion of the lining and one of the supports for a shelf;

Fig. 5 is a sectional view taken on line 5—5 of Fig. 4.

Fig. 6 is a top view showing in section a rear 50 corner of the lining and the support for the shelf;

Fig. 7 is a sectional view taken on line 7—7 of Fig. 6; and

Fig. 8 is a fragmentary sectional view of a support for a pan.

55 A refrigerator cabinet 20 is shown having an

inner lining 21 forming a compartment 22. The open front compartment 22 is closed by a door 23 surrounded by gaskets 30. A heat absorber in the form of an evaporator 24 is disposed in the upper part of the compartment 22. The evaporator 24 supports a plurality of ice trays 25. A pan 26 is carried below the evaporator 25 in which foods to be frozen may be stored. A plurality of shelves 27, 28 and 29 are carried by the lining 21. These shelves are disposed one above the other 10 and in staggered relation. The space below the pan 26 is cooled mainly by convection and due to the staggered arrangement of the shelves, the air follows a zigzag course.

Referring more to the details of the embodiment of the invention, the outer sheet metal shell 31 is provided at the front with inwardly turned flanges 32 and rearwardly turned flanges 33. The lining 21 is provided at the front with outwardly turned flanges 35 and forwardly turned flanges 20 36. The flanges 33 of shell 31 and flanges 36 of lining 21 are aligned and four frame members 38 (the vertical member at opposite sides not being shown) surround these flanges 33 and 36. Four breaker strips 39 are disposed on the opposite 25 side of these flanges and are secured to the frame members 38, as by screws (not shown), and thereby clamp the flanges 33 and 36, the frame members 38 and the breaker strips 39 in position. The cabinet is more fully disclosed in my co-pending application Serial No. 102,368 filed September 24, 1936.

The evaporator 24 comprises a shelf 41 and a coil of pipe 42 hermetically secured to the bottom thereof. The evaporator is carried by the 35 top of the lining 21 by hangers 44 and screws 45 and 46. The evaporator extends substantially across and substantially from the front to the rear of the compartment 22 and the shelf 41 thereof supports four ice trays 25.

The pan 26 is provided with lips 48 which are carried by runs 49 on opposite sides of the cabinet. The runs 49 are rods formed of wire and the ends of each are threaded into buttons 51 and 52. Buttons 51, at the rear of the lining, 45 abut the rear wall of the lining and the threaded ends of rods 49 extend through holes in the lining. Nuts 53 are threaded on the rods and thereby clamp the buttons 51 and the rear ends of the rods in place. The front ends of rods 49 are bent 50 at right angles and the threaded ends of these rods extend through holes in the side walls of the linings. Nuts 54 are threaded on the rods and thereby clamp the buttons 52 and the front ends of the rods in place. The pan 26 spans the 55

evaporator 26 so as to catch all drip therefrom. The pan 26, however is spaced from the walls of the lining and the door 23 to permit the circulation of air thereabout. The pan 26, being disposed directly below the evaporator, can be used as a frozen food container and as an absorber for heat from the air thereabout.

The shelves 27, 28 and 29 are each supported at three points; namely, at three corners. The rear edge of each shelf is disposed adjacent the rear of the lining and an edge of shelf 27, and an edge of shelf 29, is disposed adjacent the right side of the lining and an edge of shelf 28 is disposed adjacent the left side of the lining. The right rear corner of the lining 21 is provided with shelf supports for the shelves 27 and 29 and the left rear corner of lining 21 is provided with a shelf support for shelf 28. These shelf supports each include a triangularly shaped ledge 56 which is secured to the opposite side of the corner of the lining by screws 57. The corner of the shelf can rest on this ledge. A triangular clip 58 is disposed above the shelf corner and is secured to the ledge 56 by a screw 59, there being a spacing bushing 61 interposed between the ledge 56 and clip 58, the length of which bushing being substantially equal to the thickness of the beaded edge of the shelf. The shelf is rounded at this corner in order to accommodate the bushing 61.

The support for the front edge of each shelf includes a lug 62 secured to the lining 21 by a screw 63. The edge of the shelf rests thereon and the front edge of the shelf is substantially flush with the front edge of the lug. The lug is non-circular in cross section and preferably rectangular and a clip 64 cooperates with the lug and shelf for holding the corner of the shelf in position. The clip 64 includes a hook portion 65 which is arranged to embrace the opposite sides and the bottom of the lug 62 and includes a top portion 67 which is arranged to overlie the bead on the shelf. Similar supports are provided at the rear of the lining, which supports are positioned at the edges of the shelf remote from the respective rear corner support. The clips 64 at the rear prevent sidewise movement of the shelves while the clips in the front prevent forward movement of the shelves.

In assembling, one corner of the shelf is inserted between the ledge 56 and clip 58, the other rear corner resting on a rear lug 62 and the front corner resting on a front lug 62. The clip 58 and ledge 56 will prevent the shelf from tilting or teetering. The clips 64 are then placed in position, i. e., the top portion 66 is placed over the bead of the shelf and then the clip is slid toward the lug 62 and by so doing the hook portion 65 slides over the lug as shown. The clips 64 not only prevent forward or sidewise movement of the shelves but also prevent accidental lifting of the shelves.

One of the main features of my invention is the manner in which the air is circulated in the food storage compartment. It will be noted that the left edges of shelves 27 and 29 stop short of the left side of the compartment lining and the right edges of the intermediate shelf 28 stop short of the right side of the compartment lining. Since the shelves are imperforate, they form barriers to free circulation of air and the air is caused to flow horizontally between the shelves. Due to convection, air, which is cooled in the upper part of the compartment by the evaporator 25 and the adjacent elements including the pan 26, will flow downwardly and the warm air

will flow upwardly and, because of the arrangement of the shelves, both upward and downward currents will flow in zigzag paths. These paths, it will be noted, are predominantly horizontal. Eddies will be established throughout the paths of the air with the result of the tendency to cool the entire shelf storage space to the same temperature. The lining 21 being made of sheet metal will absorb heat from the interior of the compartment and will conduct the same to the upper part where it is absorbed by the evaporator. Likewise, due to the large shelf area heat will be reflected from the food to the shelves and from the shelves to the colder lining and the upper colder part of the compartment. Obviously, there will be an increment of temperature downwardly in the compartment but this increment will be minimized due to the aforementioned eddies, conduction through the lining and reflection of heat. In this manner desirable temperatures are maintained in the cabinet with minimized circulation. This is advantageous in that foods will not be dehydrated quickly, particularly in the space below the lowest shelf 29, and in this manner, the so-called "hydrator" can be eliminated for in fact the entire lower portion of the compartment functions as a high humidity chilling chamber.

There is an advantage in maintaining different sections of the compartment at different temperatures. Some foods, such as vegetables can be maintained at a relatively warmer temperature and when stored in the lowest part of the compartment, they are maintained at such desirable temperature with the added advantages that the relative humidity is high enough to prevent dehydration while the circulation of air is sufficient to prevent the growth of mold.

Another advantage of the shelf arrangement lies in the close vertical arrangement of the shelves whereby a large shelf area is available yet tall articles such as milk and beverage bottles can be stood upright. The tall articles can be placed, as shown, on that end of a shelf which is not covered by the next upper shelf.

If desirable, the front edges of the shelves 27, 28 and 29 can stop short of the door 23, as shown, to permit a freer circulation of air. In the preferred embodiment, transparent shelves such as glass shelves are used so that they in themselves are not obstructive to vision.

From the foregoing it will be seen that I have provided a refrigerator cabinet in which several regions of desirably distinct temperatures are maintained. Due to the impeding of the flow of air, the evaporator can be decreased to a relatively low temperature whereby water, within the ice trays 25, can be frozen quickly and yet the food storage compartment will not be decreased to an undesirable temperature. Also the region directly below the evaporator, namely that containing the pan 26, will be maintained at below freezing temperature for storing frozen foods. And, as previously pointed out, by the present construction, desirable relatively high humidity conditions are maintained in the food storage compartment.

While the form of embodiment of the present invention as herein disclosed constitutes a preferred form, it is to be understood that other forms might be adopted, all coming within the scope of the claims which follow:

I claim:

1. The method of producing refrigeration with in a refrigerator cabinet while maintaining a

high humidity within the food storage section of the cabinet which method consists in establishing a sharp freezing temperature in a zone at the upper portion of said cabinet and thereby causing the air which is cooled by said zone to travel, and retarding the movement of the air in the food storage section by causing the air to flow in a zig-zag course in said section.

2. The method of producing refrigeration within a refrigerator cabinet while maintaining a high humidity within the food storage section of the cabinet which method consists in establishing a sharp freezing temperature in a zone at the upper portion of said cabinet and thereby causing the air which is cooled by said zone to travel and retarding the movement of the air in the food storage section by causing the air to flow in a predominately horizontal zigzag course in said section.

20 3. The method of producing refrigeration within a refrigerator cabinet while maintaining a high humidity within the food storage section of the cabinet, which method consists in establishing a sharp freezing temperature in a zone at the upper portion of said cabinet and thereby causing the air which is cooled by said zone to travel, and retarding the movement of the air in the food storage section by directing it through a zigzag course in said section established by the arrangement of shelves in the section and causing the

warmed air rising in said section to follow a zig-zag course across said shelves.

4. The method of producing refrigeration within a refrigerator cabinet while maintaining a high humidity within the food storage section of the cabinet, which method consists in establishing a sharp freezing temperature in a zone at the upper portion of said cabinet and thereby causing the air which is cooled by said zone to travel, and retarding the movement of the air in the food storage section by directing it, through a predominately horizontal zigzag course in said section established by the arrangement of shelves in the section and causing the warmed air rising in said section to follow a predominately horizontal zigzag course through said section across said shelves.

5 5. The method of refrigeration which consists in establishing a zone of low temperature and relatively low humidity in communication with a zone of relatively high temperature and high humidity through a restricted passage and causing the cooling produced in the first mentioned zone to promote a slow circulation of air from the second mentioned zone to the first mentioned zone through said passage and a return of the air from the first mentioned zone to the second mentioned zone through said passage.
